UNITED STATES PATENT OFFICE.

EDWARD J. DU BOIS AND GEORGE C. DU BOIS, OF ALBANY, NEW YORK, ASSIGNEES TO DUBGIS MACHINE SHOP, INC., OF ALBANY, NEW YORK, A CORPORATION OF NEW YORK.

TOOL-SUPPORT FOR LATHES.

1,323,682.

Specification of Letters Patent.

Patented Dec. 2, 1919.

Application filed February 17, 1917. Serial No. 149,178.

To all whom it may concern:

Be it known that we, EDWARD J. DU BOIS and GEORGE C. DU BOIS, citizens of the United States, residing at Albany, county 5 of Albany, and State of New York, have invented certain new and useful Improvements in Tool-Supports for Lathes, of which the following is a specification.

Reference may be had to the accompanying drawings, and the reference characters marked thereon, which form a part of this specification. Similar characters refer to similar parts in the several figures therein.

The invention relates to means for supporting a tool or tool-holder at different heights and tilted at different angles of elevation, as for use in a lathe.

The principal objects of the invention are to facilitate adjustment in height, as well 20 as in the angle of elevation, of the tool or tool-holder; and to more securely clamp the tool or tool-holder in adjusted position.

Other objects will appear in connection with the following description.

Figure 1 of the drawings is a view in side elevation of a tool-support embodying our invention.

Fig. 2 is a view in front elevation of the same.

Fig. 3 is a top plan view of the same.

Fig. 4 is a vertical cross-section of the same taken on the broken line 4—4 in Fig. 3.

Fig. 5 is a view in perspective of the bolster detached.

Fig. 6 is a top plan view of the bolster-supporting washer detached.

Fig. 7 is a vertical central cross-section of the same taken on the broken line 7—7 in Fig. 6.

Fig. 8 is a cross-section of the same taken on the broken line 8—8 in Fig. 6.

Referring to the drawings wherein the invention is shown in preferred form, 1 is a tool-post-support adapted to engage a slide-rest (not shown), as found in the ordinary lathe.

A tool-post, 2, is mounted upon the support, 1, in the usual manner, said tool-post having the usual clamp-screw, 3, and being 50 provided with the transverse slot or opening, 4, adapted to receive a tool or tool-holder, 5, in position to be engaged by the clamp-screw, 3.

A bolster-supporting washer, 6, is supported upon the tool-post-support, 1, enclosing 55 the tool-post, 2.

This washer, 6, has on its upper side intersecting bolster-supporting seats, 7 and 8, formed upon the washer at different heights, as by cutting the seat, 8, more deeply than 60 the seat, 7. Each of these seats, 7 and 8, is concavely curved and roughened by means of a series of transverse steps or ribs, as shown.

A bolster, 9, of a width to pass freely 65 through the transverse opening, 4, in the tool-post, is formed with a convexly curved surface, 10, adapted to alternatively engage the several seats, 7 and 8, on the washer, 6.

The curved surface, 10, of the bolster is 70 formed with a series of transverse steps or ribs, as shown, adapting it to interlockingly engage the stepped seats, 7 and 8.

A tool-holder, 5, is adapted to be inserted in the usual manner through the opening, 4, 75 in the tool-post, and is adapted to rest upon the upper flat side, 11, of the bolster, 9, against which it is clamped by means of the clamp-screw, 3.

The operation of the device is as follows: 80

The clamp-screw, 3, being loosened, the bolster, 9, is seated in whichever of the seats, 7 or 8, it is desired to use.

The tool or tool-holder, 5, is inserted through the opening, 4, in the tool-post resting upon the flat side, 11, of the bolster, 9, and the bolster is then adjusted upon the seats, 7 or 8, to obtain the desired angle of elevation of the tool-holder.

In this adjusted position the parts are 90 securely clamped together by setting up the clamp-screw, 3, to tightly clamp the tool-holder, 5, against the bolster, which in turn is securely clamped against the washer, 6, supported by the tool-post-support, 1.

From time to time the adjustment of the tool-holder can be varied by loosening the clamp-screw, 3, and changing the position of the bolster, 9, upon its seat, and also by swinging the tool-holder, bolster, washer, 6, 100 and tool-post all about the axis of the tool-post. When the clamp-screw, 3, is loosened, the washer, 6, can be rotatably adjusted to bring either the seat, 7, or the seat, 8, in line with the opening, 4, in the tool-post, as 105 may be desired.

A tool, 12, is carried by the tool-holder, 5, it being immaterial whether said tool is integral with, or separate from the tool-holder.

We have shown the upper flat surface, 11, of the bolster roughened by means of transverse steps or ribs whereby it is adapted to make better frictional engagement with the tool-holder, 5.

The steps or ribs on the seats, 7 and 8, and upon the seating surface, 10, of the bolster, are so formed that the steps or ribs on the bolster interlockingly engage the steps or ribs on the seat, 7 or 8, so that it is impossible for the bolster to slip out of its adjusted position in use, so long as the clamp-screw, 3, remains tightly set up.

We have shown the stepped seats, 7 and 8, formed diametrically of the washer, 6, whereby the tool and the tool-supporting bolster are located directly in line with the clamp-screw, 3.

We have also shown side walls on the washer, 6, on opposite sides of the respective stepped seats between which side walls the bolster is confined, whereby the bolster is laterally supported in position for the stepped curved surface on the bolster to accurately engage the stepped seats on the washer, 6.

What we claim as new and desire to secure by Letters Patent is

1. The combination with a tool-rest having diametrical intersecting curved bolster-seats at different heights, and of uniform width; and a tool-post mounted upon said tool-rest; of a bolster alternatively engageable with the several bolster-seats on said

tool-rest; and a clamp-screw on said tool-post coöperative with said bolster to clamp thereagainst a tool-holder.

2. The combination with a rotatively mounted tool-rest having diametrical intersecting curved stepped bolster-seats at different heights, and of uniform width; and a tool-post mounted upon said tool-rest; of a bolster having a curved stepped surface alternatively engageable with the several bolster-seats on said tool-rest; and a clamp-screw on said tool-post coöperative with said bolster to clamp thereagainst a tool-holder.

3. The combination with a tool-rest; of a tool-post mounted upon said tool-rest; a washer encircling the tool-post supported by said tool-rest, said washer having diametrical intersecting curved stepped bolster-seats at different heights, and of uniform width, with side-walls on opposite sides of the respective seats; a bolster having a curved stepped surface alternatively engageable with the respective stepped seats on said washer, and adapted to be confined between the side-walls of the respective seat; and a clamp-screw mounted on said tool-post coöperative with said bolster to clamp thereagainst a tool-holder.

In testimony whereof, we have hereunto set our hands this 6th day of February, 1917.

EDWARD J. DU BOIS.
GEO. C. DU BOIS.
